UNITED STATES PATENT OFFICE.

PAUL W. HOLSTEIN, OF COLUMBUS, OHIO, ASSIGNOR TO THE JEFFREY MANUFACTURING COMPANY, A CORPORATION OF OHIO.

MINE-CAGE.

1,168,501.

Specification of Letters Patent. Patented Jan. 18, 1916.

Application filed January 2, 1908. Serial No. 408,890.

To all whom it may concern:

Be it known that I, PAUL W. HOLSTEIN, a citizen of the United States, residing at Columbus, in the county of Franklin and State of Ohio, have invented certain new and useful Improvements in Mine-Cages, of which the following is a specification, reference being had therein to the accompanying drawing.

10 This invention relates to mine cages, and has for its special object to provide mechanism whereby a car can be run upon the cage at a landing, and held more securely in position than hitherto while the cage is being 15 lifted to the surface of the ground and there emptied of its contents.

Other minor objects will be apparent from a reading of the following specification in connection with the drawings, of 20 which—

Figure 1 is a cross sectional side elevation of the mine cage in position at the bottom of its shaft, and adjacent parts of the mine. Fig. 2 is a similar cross sectional view at an 25 intermediate landing likewise showing adjacent parts of the mine, the upper part of the cage being broken away. Fig. 3 is a view in side elevation of the cage at the upper limit of its travel and of the mechanism for dumping the mine car, the tilting platform being shown in position to discharge the contents of the car. Fig. 4 is a plan view of the car, one half being shown in section, with horizontal cross section of the shaft. Fig. 5 is 30 an end elevation of the mine cage. Fig. 6 is an end elevation of the mine cage. Fig. 6 is a perspective view of the safety catch mechanism.

The cage comprises essentially two parts, the sling frame A and the tilting platform H, pivotally secured to each other at their lower ends. The sling frame can be most satisfactorily constructed of structural steel, as shown in the drawings, consisting of the vertical side channels A² joined by the upper 40 horizontal channels A¹ and the lower horizontal channel A³. To the outside faces of the channels A² are secured guide blocks B which engage with the slides C which may be wood or metal strips, to hold the cage in place laterally, while permitting freedom of motion vertically. Riveted to the top side of the upper flange of the channels A¹ is the yoke D¹ through which the draw-bar D passes. Riveted to the under side of the 45 lower flanges of the channels A¹ and mid-

way between the ends of the channels is the plate A⁴. Through a hole in the center of this plate the draw-bar D is guided in its vertical motion. By means of the spring D² surrounding the draw-bar and placed between the under side of the yoke D¹ and the nut D³ upon the draw-bar, a yielding suspension is provided so that the car will be lifted without shock, and a jerky motion in the hoisting mechanism will be to a large extent absorbed.

The cage is provided with the safety device indicated as a whole by E. Mounted in brackets E⁹ carried by the channels A² is the shaft E², keyed to which are the toothed cams E¹. A chain E⁴ attached to the under side of the segmental sheaves E⁵ at one end, and at the other to the clamp E¹⁰ secured to the draw-bar D holds the toothed cams out of engagement with the slide whenever there is tension in the hoisting rope. When for any cause this tension is released, the spring E⁷ throws the cams into engagement with the slide and any small descent of the car causes them to sink deeper into the slide, as they revolve about the shaft E² until the cam surface impinges on the upper face of the inner surface of the housing E⁸ which is preferably cast integral with the bearing brackets E⁹. The traction block E³, integral 80 with the plate E¹¹ of the bracket casting, forms with the brackets a shoe which engages with the slide and prevents the lateral displacement of the cage, as a whole, under the side thrust of the revolving cam E¹. The housing E⁸ assists the shaft bearing proper in preventing the cams from turning clear over, when they are thrown into action. Tightening the hoist rope will immediately throw these cams out of engagement 90 leaving the cage free to slide up or down.

A canopy is provided to protect workmen in the cage from falling bodies and consists of the two plates F¹—F² which are hinged to the plate F⁴, the latter being secured to the top of the upper flanges of the channels A¹. To the under sides of the plates F¹—F² are riveted the plates F³, the inner edges of which abut against the central parts of the sling frame, thus serving to hold the two 100 sides of the canopy in horizontal position, while at the same time strengthening the canopy structure, as a whole. By hinging the canopy in this manner either of the sides can be swung into a vertical position to per. 110

mit of the lowering down the shaft of rails, long pieces of timber, etc.

The bearing supporting plates G^1 for the tilting frame are riveted to the inner faces 5 of the lower ends of the channels A^2 and carry the bearing blocks G^2 , in which is mounted shaft G . Pivoted upon this shaft are the vertical channels H^1 of the tilting frame. The upper ends of which are joined 10 by the shaft H^4 rotatably mounted therein. In this manner the tilting frame is secured at the bottom and a little to one side of the sling frame. Its center of gravity, as a whole, being normally in the vertical plane 15 of the channels A^2 so that the shaft H^4 rests by the action of gravity against the brackets H^6 secured to the upper end of the sling frame.

The shaft H^4 carries a pair of rollers H^3 20 which engage with guides H^5 located at the top of the shaft to give the platform a forward movement when the sling frame is raised vertically so that the contents of the car carried by the platform may be discharged. The guides are curved, as shown 25 in the drawings, in such a way that this dumping movement is gradual and takes place without shock to the car. The vertical boards H^2 , which form a continuation of the upper ends of the guide rails H^5 , cause the 30 car to be maintained at the same tipping angle, *i. e.*, about 45° , if the sling frame is raised above the tipping plate.

Riveted to the channels H^1 near their 35 lower ends are the channel beams H^7 which are braced thereto by the plates H^8 and the diagonal struts H^9 . The mule guard plates H^{10} are secured to the channels H^1 and the struts H^9 . The channel beams H^7 with the 40 end channels H^{12} and the central I-beam H^{11} form a horizontal framework upon which the car-supporting tracks I^1 and floor boards J are supported. The latter are suitably secured to the end channels H^{12} upon 45 which they rest. The tracks I^1 are made in two sections, as shown, each section being hinged at its outer end to the end channels H^{12} by means of the bearing brackets M secured thereto, the shafts I^2 mounted therein and the plates M hinged to the shaft, and riveted to the rails. The two rails of each 50 section of the track are connected together by the channels N riveted to the under side of the rail-flanges and braced by the plates N^1 . Also riveted to the under side of the rail-flanges are the bumpers I^3 which rest upon the upper face of the I-beams I^4 hinged at one end to the shaft O mounted in the brackets O^1 secured to the inner faces of 55 the end channels H^{12} . Three other tie-rods O^2 serve to connect and hold in rigid relation to each other the channel beams along the remainder of their length. These channel beams are thus free to swing upon a 60 horizontal axis through the small angle lim- 65

ited in an upward direction by the channels H^{12} and I-beams H^{11} and in a downward direction by the stirrup I^5 suspended from the central I-beam H^{11} . When therefore the mine cage is at the bottom of the shaft, as 70 in Fig. 1, and the free end of the channels I^4 are supported by the board P the track-rails are held in a horizontal position so that a mine car may be run on or off the same from the stationary tracks of the mine galleries. 75 At an intermediate landing supports for the beam I^4 are provided in the L-shaped levers K pivoted to the rock shaft K^2 which may be rotated by a system of levers and rods K^3 , K^4 , K^5 and K^6 . When the cage is moving upward if these levers K have been inadvertently left in operative position, they will automatically be thrown out of the path of travel of the cage. On the other hand, if 80 the cage is descending and if by the lever K^6 , the levers K have been thrown into operative position the channels I^4 will be swung upward relatively to the channels I^7 and in contact therewith, so as to elevate the tracks 85 to a horizontal position. 90

When the mine car Q has been moved on to the cage and the cage begins its ascent, the track sections swing about their pivotal supports until their inner ends rest upon the lower flange H^{12} of the central I-beam H^{11} 95 and the car, as a whole, is lowered relatively to the cage until the axles Q^1 or any other suitable projection of the car settles into the notches I^7 formed in the skids I^6 until the body of the car rests upon the skids. These skids are secured to the platform boards J . By this simple expedient the car is securely 100 maintained in position upon the tilting platform, while the latter is being moved up and down the mine shaft and when it is being tipped at the surface of the mine without putting any strain upon the car wheels, or 105 running gear.

In order to stop the car upon the tilting platform exactly at that point where the car axles will be directly above the notches I^7 , the latch L notched to receive the downwardly projecting part of the L-shaped lug L^2 , attached to the bottom of the car, is 110 pivotally mounted in the latch carrying block L^6 . This block is free to slide longitudinally in suitable guideways formed in the base block L^9 , which is secured to the platform boards. The block L^{10} is held in 115 position at one end of its range of movement by the spring L^3 which takes the shock of the sudden contact of the lug L^2 of the moving car with the latch L . The latch L is normally held in engagement with the lug by the spring L^4 acting through the rod L^5 , lever L^6 and the arm L^7 keyed to the shaft L^{12} on which the latch is rigidly mounted. At the lower landing the tugger R is installed consisting of the arm R^1 120 keyed to the rock shaft R^2 to which is also 125

keyed the arm R^3 . This arm contacts with the end of the rod R^4 , which is suitably mounted on the mine floor, and is provided with the bumper R^5 adjacent to and in line with the bumper L^{15} on the end of the rod L^5 . A spring R^6 holds the bumper R^5 normally away from the bumper L^{15} . An oncoming mine car automatically operates the tucker R , and through the rod L^5 and lever 10 L^6 , releases the latch L , leaving the car on the cage free to move off which it does when the oncoming car strikes its bumpers. The oncoming car is then caught by the latch and held in position on the cage.

15 What I claim is:

1. In a mine cage, the combination of two adjacent track sections pivoted at their outer ends and having their inner ends arranged to swing to points below the normal 20 lines of the tracks, means for holding the track sections level at landings and adapted to permit said inner ends to move down to relatively low positions at points in their travel remote from the landings, substantially as set forth.

2. In a mine cage, the combination of wheel supports, longitudinal skids, arranged to be under the body of a car in position 30 on the cage, and means for lowering a car until the car body rests on said skids, substantially as set forth.

3. In a mine cage, the combination of wheel supports, longitudinal skids, arranged to lie under a car body when in position on 35 the cage, means for lowering a car until the body rests on said skids, and means on said skids for preventing longitudinal motion of the car relatively to the skids, substantially as set forth.

40 4. In a mine cage, the combination of wheel supports, longitudinal skids arranged so as to be under the body of a car on the cage, means for lowering a car until the body rests on said skids, and means for 45 preventing longitudinal motion of the car relatively to the skids while in contact therewith, substantially as set forth.

50 5. In a mine hoist, the combination of a cage adapted to move vertically in a shaft and provided with a horizontally yieldable latch for holding a car in longitudinally fixed position thereon, and means attached to the shaft for releasing said latch, substantially as set forth.

55 6. In a mine hoist, the combination of a cage adapted to move vertically in a shaft and provided with a latch for holding a car in longitudinally fixed position thereon, and means attached to the shaft intermediate the limits of movement of the cage for releasing said latch, said means being operable by an oncoming car, substantially as set forth.

60 65 7. In a mine cage, the combination of a latch adapted to catch and hold in fixed po-

sition longitudinally an oncoming car, skids adapted to support the car body, and means for lowering the car until the car body rests upon said skids, substantially as set forth.

70 8. In a mine cage, the combination of a latch adapted to catch and hold in fixed position longitudinally an oncoming car, skids adapted to support the car body, means for lowering the car until the car body rests upon said skids, and means on the skids for holding the car in fixed position longitudinally, substantially as set forth.

75 9. In a mine cage, the combination of a latch adapted to catch and hold in fixed position longitudinally an oncoming car, skids adapted to support the car body, and means for lowering the car until the car body rests upon said skids, said means being free to operate as the cage commences to ascend, substantially as set forth.

80 10. In a mine hoist, the combination of a cage adapted to move vertically in a shaft and provided with a horizontally yieldable latch for holding a car in longitudinally fixed position thereon, and means normally retracted from the path of the car and attached to the shaft for releasing said latch, substantially as set forth.

85 11. In a mine hoist, the combination of a cage adapted to move vertically in a shaft and provided with a latch for holding a car in longitudinally fixed position thereon, and means attached to the shaft and normally retracted from the path of the car for releasing said latch, said means being operable by an oncoming car, substantially as set forth.

90 12. In a mine cage, the combination of two adjacent track sections pivoted at their outer ends to the cage frame and normally free to swing about the said pivots to downward inclined positions, and mechanism for lifting the track sections to horizontal aligned positions when the cage moves downward into alignment with a landing, substantially as set forth.

95 13. In a mine hoist, the combination of a vertically movable cage, two separate track sections pivoted at their ends respectively to the ends of the frame of the cage and adapted to move about the said pivots to normal downward inclined positions, a track section support pivoted at one end to the frame of the cage and adapted to engage the track sections intermediate its ends, and means for swinging the said support upward relative to the cage to lift the track sections into horizontal positions, substantially as set forth.

100 14. In a mine cage, the combination of wheel supports, longitudinal skids arranged to lie under a car body when in position on the cage, and means for changing the relative positions of the wheel supports and the

skids whereby the weight of the car is transferred from the former to the latter, substantially as set forth.

15. In a mine cage, the combination of
5 wheel supports, skids arranged to lie under a
car body when in position on the cage, means
for changing the relative positions of the
wheel supports and the skids whereby the
10 weight of the car is transferred from the
former to the latter, and means for preventing
longitudinal movement of the car relatively
to the skids, substantially as set forth.

16. In a mine hoist, the combination of a
cage adapted to move vertically in a shaft,
15 a latch adapted to engage a car on the cage
to hold it in longitudinally fixed position,

a horizontally movable element connected
with the latch, and a horizontally movable
device attached to the shaft in alinement
with said element when the cage is at a land- 20
ing, and a device controlled by the move-
ment of an oncoming car for moving the
said device into engagement with the said
element whereby the latter is actuated to
release the latch, substantially as set forth. 25

In testimony whereof I affix my signature,
in presence of two witnesses.

PAUL W. HOLSTEIN.
